UNITED STATES PATENT OFFICE.

VICTOR THOMPSON, OF VANCOUVER, BRITISH COLUMBIA, CANADA.

TELEPHONE-CALL-REGISTERING DEVICE.

1,141,367.

Specification of Letters Patent.

Patented June 1, 1915.

Application filed October 13, 1914. Serial No. 886,538.

To all whom it may concern:

Be it known that I, VICTOR THOMPSON, a subject of the King of Great Britain, and a resident of the city of Vancouver, in the Province of British Columbia, Canada, have invented certain new and useful Improvements in Telephone-Call-Registering Devices, of which the following is a specification.

10 My invention relates to improvements in telephone call registering devices, and the object of my invention is to devise a simple and inexpensive means capable of being connected to an ordinary telephone circuit and the use of which makes it impossible for the user of a telephone to make a call without first paying for same, thereby eliminating entirely the monetary loss which is suffered by telephone companies at the present time due to unpaid calls, since with my device every call is paid for in advance. The leakage in such calls obtaining at the present time is thus prevented, in consequence of which the returns to the company are 25 greater, making it possible to carry out improvements in the system which will be mutually beneficial to both the company and the general public. I attain this object by the means illustrated in the accompanying drawings in which—

Figure 1 is a side elevation of my device, the box being shown in section. Fig. 2 is a plan view, the cover being removed. Fig. 3 is a front end view, the cover being removed. 35 Fig. 4 is a diagrammatic view illustrating in its simplest form the manner in which my device operates.

Similar figures of reference indicate similar parts throughout the several views.

40 1 is a box of suitable material and dimensions which incloses the mechanism of my device, which box may have a hinged lift-up cover 1^a, such as shown in Fig. 1.

2 is the base on which the mechanism is 45 supported, which base may be of any suitable material and which is removably carried in the box 1, as shown in Figs. 1, 2, and 3.

3 and 4 are upwardly extending brackets 50 secured oppositely to each other on each side of the base 2.

5 is a shaft rotatably supported in the brackets 3 and 4.

6 is a ratchet wheel secured to the shaft 5. 7 is an electro-magnet secured to the 55 base 2.

8 is a lever swingably carried by the shaft 5, which lever extends backwardly so that its outer end is approximately above the center of the magnet 7 and normally free 60 therefrom.

9 is a pawl swingably carried by the lever 8 and normally in engagement with the teeth of the wheel 6, being held in place by means of the spring 10, one end of which is secured 65 to the lever 8 while its free end bears against the back of the pawl 9.

11 is a vertical post member secured at its lower end to the base 2 and having a stop portion 12 formed at a suitable position 70 thereon, which stop portion is provided for the purpose of limiting the upward movement of the lever 8.

13 is a spring connected to and extending between the upper end of the member 11 75 and the lever 8, the purpose of which spring is to return the lever 8 to its normal position after having been depressed, as more fully hereinafter described.

14 is a table of electrical conducting material, swingably supported at a suitable height above the base 2 in any suitable manner, such as by hinging its inner end to the bar 15, which bar is secured to the base 2. 80

16 are slots formed in the table 14. 85

17 is a spring member secured to the base by one end, its other end engaging the table 14 on the underside so as to keep the table in an approximately horizontal position when free of any weight thereon, as herein- 90 after mentioned, while at the same time permitting it to be depressed by the weight of a suitable coin when the same is placed on the table.

18 is an electrical terminal secured to the 95 base 2 and positioned under the free end of table 14. This terminal is provided with a threaded portion 19 carrying an interiorly threaded cap 20, on the point of which the table 14 rests when in the depressed position, and which cap may be screwed upwardly or downwardly to vary the distance between it and the table when the table is in the horizontal position.

21 is a chute secured to the box 1 in such a 100 manner that a suitable coin passed through

the opening 22 provided for that purpose will fall on to the chute and be directed thereby on to the table 14 to depress same.

5 23 are slots formed in the chute 21 similar to the slots 16 already mentioned.

24 are fingers secured to the shaft 5 and in line with the slots 16 and 23 so that when the shaft is rotated the fingers 24 will pass through the slots and come in contact with a 10 coin lying on the table 14, the coin being shown dotted in Fig. 2.

15 25 is a spring member secured to the base 2 and engaging the teeth of the wheel 6 so as to prevent backward movement of the wheel.

26 is an opening through one side of the box 1 through which the indicator may be seen.

27 is a glass covering the opening 26.
20 28 is a disk of any suitable material secured on the inside of the box and extending across the opening 26 and behind the glass 27, on which disk is marked in approved fashion an index showing the number of paid calls the device is capable of registering for a certain fixed sum.

25 29 is a pointer which passes through a central opening in the disk 28 and which is secured into the end of shaft 5 to be rotated therewith, which pointer indicates at a glance the number of calls used by the subscriber from the time the coin was placed on the table 14.

30 30 is an electric wire from the magnet 7 to one of the telephone circuit wires, 31 in Fig. 4.

32 is a wire from the magnet to the table 14.

33 is a wire from the terminal 18, which 40 wire is "ground" in any suitable manner.

34 is a wire which completes the magnet circuit, being connected at one end to the wire 31 of the telephone circuit, its other end being connected to a battery 35.

45 36 is a switch placed at a suitable point in the magnet circuit to "make" or "break" same.

37 is a "tell-tale" lamp which indicates by flashing when the magnet circuit is complete.

50 38 is a "ground" wire from the other pole of battery 35.

Having thus indicated the principal parts of my invention I will now describe the manner in which it operates. My device is placed near the telephone in any suitable position and connected to the telephone circuit in any approved fashion. Although a method of wiring is shown in Fig. 4, it is 55 not intended that this should illustrate any specific system; this view is only indicative of the simplest form of connecting up my device and serves to show the mechanical operation of the device itself rather than the operation of any entire system. With

this in mind, refer now to Fig. 4, in which the device is located in a home or office near the subscriber's telephone, while the wire 34 leads to the battery 35, which is located in the central operating station, as also is 70 the switch 36 and the lamp 37, the switch being under control of, and the lamp in sight of, the operator. Referring now to Figs. 1 and 4, it will be seen that a complete electrical circuit is obtained when the table 75 14 is in contact with the cap 20 of the terminal 18 and the switch 36 closed, the current then passing from the battery 35 through the switch 36, the lamp 37, the wire 34, part of the wire 31, the wire 30, the magnet 7, the 80 wire 32, the table 14, the terminal 18, and the "ground" wire 33, the other "ground" wire 38 completing the circuit. It will also be seen that this circuit is automatically broken when the table 14 is free of the cap 85 20, so that although the switch 36 is closed by the operator no current will pass, and this will be indicated by the lamp 37, which will not flash. Since the operation of the device depends on the completion of the magnet circuit it will be evident that the table 14 must be always in the depressed position and in contact with the cap 20 before the circuit can be completed by the closing of the switch 36 by the operator, and in order 90 to depress the table a coin, representing the amount fixed by the telephone company as payment for a fixed number of calls, must be passed through the opening 22 onto the table, which, as hereinbefore mentioned, is 100 adapted to be depressed by the weight of such a coin. Assuming therefore that the required coin is resting on the table 14 depressing same, that fifty calls are allowed for such a coin, and that the pointer 29 is at 105 the starting point, the operation is as follows:—The subscriber calls up the operator, asking for a number in the usual manner. Before connecting the party calling to the party called, the operator closes the switch 110 36, completing the magnet circuit as already described. The current, passing through the magnet 7, energizes same, causing the lever 8 to be drawn down against the pole of the magnet, so that the pawl 9, being normally engaged in one of the teeth of the wheel 6, forces the wheel around a sufficient amount to cause the pointer 29 to register one call on the index and also moves at the same time the shaft 5 and the fingers 24 a 115 corresponding amount. On the switch being opened again by the operator the magnet is de-magnetized, and the spring 13 draws the lever 8 up against the stop 12, the pawl 9 also rising with the lever to be forced into 120 engagement with the succeeding tooth of wheel 6 by the spring 10. Each time a call is made by the subscriber this operation is repeated, from which it will be evident that the wheel 6, shaft 5, and fingers 24, and also 125 130

the pointer 29 will, by a series of such operations, be turned through a complete circle in the direction of the arrow in Fig. 1. Referring now to Figs. 1 and 2, it will be noted that at a certain point of this travel the fingers 24 will come in contact with the coin resting on the table 14, and as the movement of the fingers continues they will carry the coin before them and finally throw it off the table into the bottom of the box 1, as indicated in Fig. 1. The arrangement of the fingers 24 with relation to the other parts of the device is such that when the last call, or in the case under illustration, the fiftieth call, is registered, they will tip the coin off the table. As soon as the coin leaves the table, the spring 17 forces the table upward, breaking the magnet circuit, the circuit remaining broken at this point until another coin has been placed on the table. In the event of the subscriber calling the operator and asking for a number, there being no coin on the table, this will be indicated to the operator when closing switch 36 to register the call, since, the circuit being broken at the table, the "tell-tale" lamp 37 will not flash and the operator will not connect the parties until it is shown by the flashing of the lamp that the required coin has been placed on the table of the device in the office or home of the party calling, thus enabling the parties to be connected and the call to be registered against the party calling.

The box 1 may be opened by an agent of the telephone company and the coins representing registered calls collected from time to time.

It will be seen, therefore, that I have devised a simple means of insuring that every call is paid for, thereby eliminating entirely the loss of revenue suffered by telephone companies at the present time from calls which are not paid for.

What I claim as my invention is:

1. A telephone call registering device comprising a casing, a base within the casing, an electro-magnet supported on the said base, a rotatably supported shaft, a toothed wheel secured on the said shaft, a lever swingably carried by the shaft normally free of the magnet and adapted to be depressed by the magnet when magnetized, means for returning the said lever to its normal position when the magnet is demagnetized, a pawl operated by the said lever and normally engaging the said toothed wheel so as to impart progressive movement thereto at each depression of the lever, an electric terminal carried by the base, an electrical conducting table hingedly supported on the base adapted to be depressed to make contact with the said terminal by the weight of a coin when placed on the table and to be freed from contact with the

terminal when the coin is removed, means for directing a coin from outside the said casing on to the said table, means carried by the said shaft for removing the coin from the table at a predetermined point in the rotation of the said shaft, and means for magnetizing and de-magnetizing the said magnet.

2. A telephone call registering device, comprising a casing, a base removably carried within the casing, an electro-magnet supported on the said base, a rotatably supported shaft, a toothed wheel secured on said shaft, a lever swingably carried by the shaft and having its extremity above the said magnet and normally free therefrom, said lever being adapted to be depressed by the magnetizing of the magnet, means for returning the lever to its normal position when the magnet is de-magnetized, a pawl operated by the said lever and normally engaging the said toothed wheel to impart a progressive movement thereto at each depression of the lever, means for preventing backward movement of the said wheel, a vertically adjustable electrical terminal carried by the said base, an electrical conducting table hingedly supported on the base and adapted to be depressed by a suitable coin when placed thereon so as to make contact with said terminal and said magnet and to break contact therebetween when the coin is removed, members carried by the said shaft adapted to engage a coin on the said table and to remove same therefrom at a predetermined point in the rotation of the said shaft, means for magnetizing and de-magnetizing the said magnet, and means for indicating the position of the said members with relation to the said table at any time.

3. In a telephone call registering device, the combination with a normally broken electrical circuit, means for supplying current thereto, and hand operated means for making and breaking the circuit, of a suitably supported index card, each index mark thereon representing one telephone call, a pointer extending centrally through the card to indicate on the face thereof, electro-magnetic means adapted to impart progressive movement to the said pointer so that it will move successively from one index mark to the other, said electro-magnetic means being operated by the making and breaking of the electrical circuit by the hand operated means, a coin receiving plate adapted to prevent the operation of the said electro-magnetic means unless a coin is present on the plate, and means for removing the coin automatically from the plate when the pointer has completed a predetermined travel.

4. A telephone call registering device, comprising, a casing having a coin slot in one end and an opening in one side, an index

card closing said opening, a base removably carried within said casing, an electro-magnet on said base, a bracket on each side of the base and opposite to each other, a shaft 5 rotatably supported in said brackets, a toothed wheel secured on said shaft, a lever swingably carried on said shaft and having its extremity above said magnet and normally free therefrom, said lever being adapt- 10 ed to be depressed by the magnetizing of the magnet, a vertical post member secured to the base provided with a stop portion engag- 15 ing the lever in its normal position, a spring extending from the upper end of the said post member and connected to said lever, a pawl operated by the lever and normally engaging the said toothed wheel to move same in one direction at each depression of the lever, means for preventing op- 20 posite movement of the toothed wheel, an electrical terminal carried by the base, said terminal being provided with an upwardly extending threaded portion and having an interiorly threaded cap fitting the said por- 25 tion and rotatable thereon, an electrical con- ducting slotted plate hingedly supported on said base in an approximately horizontal position, one end of said plate being normally in connection with said magnet and 30 its opposite end being above said terminal and normally free therefrom, said plate being adapted to be depressed when a coin is present thereon so that its free end will contact with said cap, a coin chute between 35 the coin slot and the said plate, fingers on the said shaft adapted to engage a coin on the plate to throw the coin therefrom at a predetermined point of their travel, a pointer operated by said shaft extending 40 centrally through said index card to indicate on the face thereof, and means for magnetizing and de-magnetizing the said mag- net.

5. A telephone call registering device 45 comprising a graduated index card, a traveling pointer co-acting therewith, a normally open electric circuit, a switch inter- 50 posed in the circuit and composed of a stationary terminal member, a depressible ter- 55 minal member designed to receive and be depressed by the weight of a coin, a man- 60 ually operated switch also interposed in the circuit, mechanism operated by each closing of the circuit for imparting a step-by-step movement to the pointer, and means for au- 65 tomatically relieving the depressible terminal member of the weight of the coin co- 70 incident with the arrival of the pointer at the last indicator graduation, as and for 75 the purpose specified.

6. A telephone call registering device comprising a graduated index card, a rotatable pointer co-acting therewith, a ratchet wheel to which the pointer is connected, a

normally open circuit, an electric magnet 65 located in the circuit, a spring held armature co-acting therewith, a pawl carried by the armature and co-acting with the ratchet wheel, a switch located in the circuit and designed to receive and be operated by the weight of a coin, a manually operated switch also located in the circuit and automatic means operated at the end of the rotary movement of the pointer for relieving the coin operated switch of the weight of the 75 coin, as and for the purpose specified.

7. A telephone call registering device comprising a graduated index card, a traveling pointer co-acting therewith, a normally open circuit, a plate swingably mounted at 80 one end and to which a circuit terminal is connected, a stationary terminal contact from which the other circuit terminal leads, means for holding the plate in a normally horizontal position, a manually operated 85 switch also interposed in the circuit, a finger, and means for operating the finger to sweep the coin off the plate when the pointer arrives at the last graduation, as and for the purpose specified. 90

8. A telephone call registering device comprising a graduated index card, a rotary pointer co-acting therewith, a rotatable shaft carrying the pointer, a normally open circuit, means operated by the closed cir- 95 circuit for rotating the shaft by a step-by-step movement, fingers carried by the rotating shaft, a tiltably mounted longitudinally slotted plate through which the ends of the fingers are designed to travel and to which a 100 circuit terminal is connected, a stationary terminal member to which the opposing circuit terminal is connected, and a manually operated switch also interposed in the circuit, as and for the purpose specified. 105

9. In a telephone call registering device as described, the combination with a nor- 110 mally open electric circuit and a coin oper- ated circuit closure therefor comprising a stationary terminal member and a depre- 115 ssible terminal member designed to receive a coin and to be depressed by the weight there- of, of means for automatically relieving the said depressible member of the weight of the coin at predetermined intervals, said means comprising a rotatably mounted shaft, fingers on said shaft, and electro- 120 magnetic means adapted to be set in opera- tion by the closing of the normally open circuit to rotate the said shaft.

10. In a telephone call registering device as described, the combination with a nor- 125 mally open electric circuit and a coin oper- ated circuit closure therefor comprising a plate swingably mounted at one end and designed to receive a coin and a terminal against which the said plate is depressed by the weight of the coin of a rotatably mount-

ed shaft, a finger on said shaft and elec-
tro-magnetic means adapted to be set in
operation by the closing of the normally
open circuit to rotate said shaft and said
5 finger so as to sweep the coin off the said
plate at a predetermined interval.

Dated at Vancouver, B. C., this 24th day
of September, 1914.
